Patented Nov. 21, 1922.

UNITED STATES PATENT OFFICE.

HERBERT E. MARKS, OF GLEN OSBORNE, PENNSYLVANIA.

LATHING.

Application filed January 5, 1922. Serial No. 527,203.

To all whom it may concern:

Be it known that I, HERBERT E. MARKS, a citizen of the United States, residing at Glen Osborne, in the county of Allegheny 5 and State of Pennsylvania, have invented a new and useful Improvement in Lathing, of which the following is a full, clear, and exact description.

My invention relates to lathing, and more particularly to lathing made of plaster-board. Plaster-board is a well known article of manufacture and is used in sheets for making walls, ceilings, etc. The plaster-board usually consists of an inner layer 15 about one-fourth of an inch thick of gypsum plaster faced on both sides with heavy paper. I have found that the plaster-board if cut into strips of about the width of ordinary wood laths forms an unusually good lathing 20 material. While the plaster-board sheets may be cut into laths, a cheaper source of the material is the waste from the plaster-board mills, which can be cut up into narrow lathing strips.

25 In the drawings which illustrate the preferred embodiment of the invention,—

Figure 1 is an elevation of a strip of my lathing material in which the laths are carried on a paper backing;

30 Figure 2 is a longitudinal section through the lathing, taken at right angles to the laths themselves;

Figure 3 is a similar cross section showing a modification;

35 Figure 4 is another cross section showing still another modification; and

Figure 5 is a fragmentary perspective view showing the lath and its attachment to the paper backing in greater detail.

40 Referring to the illustrated embodiment of the invention, the laths 1 themselves consist of long narrow strips of plaster-board having about the same length, width and thickness as the usual wood laths. Each lath

45 consists of an inner layer or body 2 of gypsum plaster and has its two faces formed by the paper layers 3 and 4. The laths are formed preferably by breaking off the strips so that the edges 5 of the plaster layer are

50 rough and form an unusually good bond with the plastering to be applied. The laths may be used alone, but I prefer to make up a lathing ready for use by applying the laths 1 to a paper backing 6. The paper 6 is a

55 heavy strong paper having about the same weight and water absorptive qualities as the

paper 3 and 4 of the plaster-board. The laths 1 are applied to the paper preferably by some adhesive material, such as glue. I prefer to use a water-proof glue, or other 60 water-proof material, such as asphaltum. The material can, with a water-proof cement, be exposed to moisture without the lathing strips becoming detached. If desired, the 65 lathing may be applied to the paper by mechanical fastening means, such as staples 7, as shown in Figure 4, or the staples may be employed in conjunction with the adhesive. The lathing strips are spaced apart on the 70 paper backing preferably so that the space between the laths is not materially less than the width of the laths. This permits fewer laths to be used than when the usual wooden laths are applied. The paper backing keeps 75 the plaster from being pushed through between the laths, permitting the laths to be spaced farther apart and at the same time saving the waste plaster which falls down behind the laths when no backing is employed. In the construction shown in Figure 80 2, the laths are spaced apart by about double the width of the individual laths. Such a construction may be used for side walls. When the laths are to be used for ceilings, 85 they are preferably spaced closer together, as shown, for example, in Figures 3 and 4. The laths may have straight sides, as shown in Figure 2, or one side may be undercut or beveled, as shown in Figure 3, or both sides 90 may be beveled, as shown in Figure 4, to increase the lock of the plaster with the laths. If further locking of the plaster is desired, 95 holes, indicated at 8, may be cut through the paper, preferably along the sides of the laths 1, through which the plaster may protrude and form a lock.

The lathing is preferably made up as above described, by applying the plaster-board laths to a paper backing. The material is preferably made in long rolls so that 100 pieces may be cut off the height of the room wall or width of the ceiling and readily applied. The paper backing holds the lath in correct spaced relation so that the cut off strip of lathing material may be hung on 105 the side wall from the top and then quickly nailed into place. The fastening nails are driven directly through the plaster-board lath into the studding. The paper forming the backing 6 is used preferably with its 110 lengthwise grain at right angles to the laths, whereby its greatest strength is available

lengthwise of the roll where it is most needed. The laths are preferably, but not necessarily, cut so that the lengthwise or strongest direction of the paper layers 3 and 5 4 is lengthwise of the lath strips.

The plaster-board laths are strong and permit the lathing to be used with widely spaced studding. The paper backing keeps the plaster from falling back between the 10 laths and being wasted. The rough exposed edges of the interior plaster layer of the plaster-board form a strong bond with the plaster.

The plaster-board closely resembles, in its 15 physical qualities, the plaster which is applied. It has about the same degree of contraction and expansion, moisture-absorbing qualities, etc., so that the wall containing the plaster and plaster-board forms a much 20 more homogeneous sheet of material than is the case where other types of lathing are used. If the plaster becomes wet, there is much less likelihood of its cracking than where materials are employed which have 25 absorptive qualities differing from those of the plaster.

The lath and the paper backing have the correct "suction". This term is employed by the plasterers to define the adhesion of the 30 plaster to the lath as it is initially applied. The degree of so called "suction" is apparently dependent on the porosity or water-absorbing qualities of the lathing material. If the material absorbs water too readily, it 35 has too great or too quick suction, so that while the plaster bonds to it almost immediately, the water is drawn out too quickly and the plaster does not properly set. On the other hand, if the material has little absorbent qualities, it is said to have no "suction", and it is difficult to apply the plaster. The plaster-board lath has about the right "suction" so that the plaster can be readily applied by the workman. The combination 40 of the gypsum plaster core and the paper facing on the lath, together with the paper backing, give the proper "suction" and ready adhesion of the plaster to the lathing material.

50 By the use of my lathing material, one coat may be eliminated from the usual present practice required by many city ordinances for building construction. In applying plaster, particularly on wooden laths, 55 a rough coat is applied and this is allowed to set. The water goes into the wooden laths and the laths apparently expand. This first rough course of plaster cracks into a great many small cracks. After the cracking 60 period is over, a so-called scratch coating is applied, and then a third or finishing coat applied over the scratch coat. In using my plaster-board lathing, the cracking of the first coat is prevented, so that the rough and 65 scratch coats may be combined into a single

coat, with a great saving of labor, cost and time.

By the term plaster-board as used in the specification and claims is meant the well known article of manufacture of that name 70 or its equivalent, that is to say, sheet material the body of which is composed of plaster or plastic material having physical qualities similar to plaster as regards suction. 75

The present invention is not limited to the illustrated embodiment, but may be otherwise embodied within the scope of the following claims.

I claim:

1. A narrow lath consisting of a core of plaster with its edges exposed and with paper facings on both sides, substantially as described. 80

2. A lath consisting of a core of plaster 85 with paper facings on both sides, the exposed edges of the plaster core being rough to afford a good bonding surface, substantially as described.

3. A narrow lath cut from plaster-board 90 and having the edges of the body thereof exposed, substantially as described.

4. A lathing material comprising a sheet of paper having cemented thereto strips or laths of plaster-board, such strips being 95 formed of a plaster core and having paper faces, one of which is cemented to the paper sheet, substantially as described.

5. A lathing material comprising a sheet 100 of paper having cemented thereto strips or laths of plaster-board, such strips being formed of a plaster core and having paper faces, one of which is cemented to the paper sheet, the exposed edges of the plaster core being rough to afford a good bonding surface, substantially as described. 105

6. A lathing material comprising a sheet of paper having cemented thereto strips or laths of plaster-board, such strips being 110 formed of a plaster core and having paper faces, one of which is cemented to the paper sheet, the paper having perforations therein through which the plaster may form locks, substantially as described.

7. A lathing material comprising a sheet 115 of paper having secured thereto strips or laths of plaster-board, such strips being formed of a plaster core and having paper faces, one of which lies against the paper sheet, substantially as described.

8. A lathing material comprising a sheet of paper having secured thereto strips or laths of plaster-board, such strips being 120 formed of a plaster core and having paper faces, the exposed edges of the plaster core being rough to afford a good bonding surface, substantially as described.

9. A lathing material comprising a sheet of paper having applied thereto narrow strips or laths of plaster-board, such strips 125

being formed of a plaster body and having plastic material having exposed edges to ad-
at least one paper face, substantially as de- here to an applied coating of plaster and a 10
scribed. reenforcing facing on at least one side of

10. A narrow lath consisting of a body of plaster with its edges exposed and with a paper facing on at least one side, substan-
5 tially as described.

11. A narrow lath comprising a body of

In testimony whereof I have hereunto set
my hand.

HERBERT E. MARKS.
